UNITED STATES PATENT OFFICE

127,514

DESIGN FOR A SHOE

Gus E. Bergman, Columbus, Nebr.

Application March 19, 1941, Serial No. 99,701

Term of patent 7 years

To all whom it may concern:

Be it known that I, Gus E. Bergman, a citizen of the United States, residing at Columbus, county of Platte, and State of Nebraska, have invented a new, original, and ornamental Design for a Shoe, of which the following is a specification, reference being had to the accompanying drawing, forming a part thereof, in which:

Figure 1 is a top plan view of a shoe, showing my new design; Figure 2 is a side elevational view; and Figure 3 is a rear elevational view of the same.

I claim:

The ornamental design for a shoe, as shown.

GUS E. BERGMAN.
